(57) **CLAIM**

The ornamental design for an ergonomic applicator, as shown and described.

DESCRIPTION

FIG. 1 is a front perspective view of an ergonomic applicator according to the invention;

FIG. 2 is a back perspective view of an ergonomic applicator according to the invention;

FIG. 3 is a side view of an ergonomic applicator showing my new design;

FIG. 4 is a front view thereof;

FIG. 5 is a back view thereof;

FIG. 6 is a side opposite that shown in FIG. 3;

FIG. 7 is a bottom plan view thereof; and,

FIG. 8 is a top plan view thereof.

The portions of the applicator illustrated in broken lines form no part of the claimed design. The claimed design is limited to the shaded surfaces only.
